DESIGN FOR A COMBINATION MANICURE SET OR SIMILAR ARTICLE

William J. Popp, Loudonville, N. Y.

Application December 24, 1934, Serial No. 54,591

Term of patent 3½ years

To all whom it may concern:

Be it known that I, William J. Popp, a citizen of the United States, residing at Loudonville, county of Albany, and State of New York, have invented a new, original, and ornamental Design for a Combination Manicure Set or Similar Article, of which the following is a specification, reference being had to the accompanying drawing, forming a part thereof, in which—

Fig. 1 is a perspective view of the device in open position showing the new design;

Fig. 2 is an end view thereof; and

Fig. 3 is a perspective view of the device in closed position.

I claim:

The ornamental design for a combination manicure set or similar article, as shown.

WILLIAM J. POPP.
